VARIABLE TRANSFER DIRECTIONAL COUPLER
FOR MICROWAVE ENERGYKiyo Tomiyasu and Seymour B. Cohn, Flushing, N. Y.,
assignors to Sperry Rand Corporation, a corporation
of Delaware

Application November 22, 1958, Serial No. 197,064

6 Claims. (Cl. 333—10)

The present invention relates to microwave energy transmission and control devices, and is particularly concerned with apparatus for controllable directional coupling of microwave energy between plural energy conduits.

An object of this invention is to provide a directional coupler system capable of a wide range of variation of the degree of coupling.

Another object is to provide a microwave coupling device affording extreme flexibility of application, and usable as a basis for microwave transfer or division between plural energy conducting systems, or for combining the outputs of plural energy sources.

A further object is to provide a system embodying, in combination, the feature of directional coupling between plural conduits, and the feature of availability of full energy transfer from one conduit to another, including arrangements for conveniently controlling or regulating the energy transferred.

In accordance with the present invention, a pair of conduits are arranged with contiguous or substantially adjacent sections, and a distributed coupling region is provided theretwixt for effectively achieving a modified or enlarged conduit section. Through this conduit section, directional coupling is afforded between the conduits, and by variation of the extent to which their interiors communicate, the degree of coupling or energy transferred is regulated.

The invention is described in detail in connection with the appended drawings, wherein:

Fig. 1 is a perspective view of a variable transfer directional coupling system according to the present invention;

Fig. 2 is a view of the two wave guides of the system of Fig. 1, separated for a better view of the coupling arrangements;

Fig. 3 is a group of views showing the manner in which the wave guides of Figs. 1 and 2 are relatively shifted longitudinally for variation of the energy transfer therebetween;

Fig. 4 is a pair of curves showing the manner in which the power and intensity of the transferred energy vary as a function of the extent of the effective communication aperture, the output electric field strength and power values being based on the power and intensity of the energy supplied by the source;

Figs. 5—8 are views of a modified embodiment of the present invention incorporating the features of choke joints and anti-friction bearings, Fig. 5 being a side elevation, Fig. 6 being a cross-sectional view taken on the line 6—6 in Fig. 5, Fig. 7 being an isometric view with portions broken away to show details of the choke, and Fig. 8 being a sectional view taken on the line 8—8 in Fig. 6;

Fig. 9 is a diagrammatic side elevation view of a variable transfer coupler system positioned for full energy transfer, with stations being denoted for description of the phase relationships existing along the system;

Figs. 10, 11 and 12 are vector diagrams employed in description of the invention; and

2

Figs. 13 and 14 are fragmentary cross-sectional views illustrating the provision of internal plates in the wave guide for maintaining continuity of the characteristic impedances therein.

Referring now particularly to Figs. 1 and 2, a pair of wave guides 11 and 13 have mutually adjacent narrow walls, shown as wall 15 of wave guide 11 and wall 17 of wave guide 13, in Fig. 2. An elongated opening 19 is provided in wall 17 of wave guide 13, and an elongated opening 21 is provided in wall 15 of wave guide 11. Across the latter are provided a series of inductance cross-bars, typified by cross-bars 23, for reasons which will presently be set forth.

Means are provided for enabling the user of the apparatus of Figs. 1 and 2 to adjust the effective length of the region of communication through the mutually adjacent openings 21 and 19. Such means may comprise guide blocks 27 and 29 attached to one of the wave guides and arranged to restrict the other wave guide to longitudinal sliding movement parallel and adjacent thereto.

When the relative positions of the wave guides are adjusted in such a way as to have the openings 19 and 21 entirely out of register, no energy transfer can occur between the two wave guides. As one wave guide is shifted longitudinally relative to the other, in the direction to bring about partial register of the openings 19 and 21, energy transfer is permitted from one guide to the other.

With a source 31 coupled to the left-hand end of wave guide 11 to supply energy thereto, prior to partial register of the openings, a utilization device such as a microwave energy detector and indicator 33 coupled to the right-hand end of wave guide 11 gives a maximum energy reading, and a similar device 35 coupled to the right-hand end of wave guide 13 indicates no energy arrival therethrough. As the relative positions of the wave guides 11 and 13 are shifted to bring about partial register, less of the energy arrives at utilization device 33, and an increasing amount of energy arrives at utilization device 35.

If the openings 21 and 19 have sufficient length, in relation to the wavelength of the energy from source 31 and the cross-sectional dimensions of the wave guides (particularly their greater internal dimension) and the characteristics of the openings, the presence of the inductance cross-bars 23 being taken into account, a condition will eventually be reached wherein the openings are in register to such a considerable extent that the energy transfer from wave guide 11 to wave guide 13 is complete, so that utilization device 35 receives all of the energy transmitted from source 31, and utilization device 33 receives none of the energy. Fig. 4 illustrates in dotted line the variation of relative electric field strength of the transferred energy, as a sine function of the extent of registering openings; and in the solid line graph is depicted the variation of relative power transferred as a sine-squared function of the extent of registering openings.

As to such energy as is coupled or transferred into wave guide 13, the propagation is substantially confined to the same direction as the direction of energy travel in wave guide 11. This is due to the feature of longitudinally distributed coupling, which tends to provide mutual cancellation of leftward-directed wave amplitude components coupled across from the first guide to the second at points one-quarter wavelength apart. Thus, there is substantially zero net energy propagation toward the left end of wave guide 13.

An even greater extent of registering openings between the two wave guides 11 and 13 than the above-mentioned extent for 100% energy transfer would result in at least partial retransfer of energy from wave guide 13 back into wave guide 11, the direction of propagation onward away from the source 31 being maintained. Hence, the energy arriving at utilization device 35 would be reduced, and

the energy arriving at utilization device 33 would be increased. Ordinarily, however, for the combined features of directional coupling and variable energy transfer or variable energy division between two output wave guide connections, it is advantageous to arrange the openings 19 and 21 to be of just sufficient extent for total energy transfer from the supply wave guide 11 to the other wave guide 13 when the openings have reached full register.

Fig. 3 illustrates the manner in which one wave guide 13 is shifted relative to the other wave guide 11 to provide varying amounts of energy transfer. The positions of the respective openings in the adjacent walls of wave guides 11 and 13 are indicated by the brackets 41 and 43, so that the extent of register of the openings is readily visualized in the respective views A, B and C of Fig. 3.

A calibration scale and index may be provided on or associated with the wave guides 11 and 13, for convenient indication of the amount of power diverted to the output end of wave guide 13 relative to the power supplied at the input end of wave guide 11. The remaining power is transmitted through to the output end (the right-hand end) of wave guide 11. With the openings entirely out of register, as illustrated in Fig. 3A, the total input power is transmitted straight through to the output end of wave guide 11, and as indicated by the index mark 45 over the zero of the scale markings on wave guide 11, no power is transferred into wave guide 13, and hence no power is available at the right-hand end thereof.

As indicated in Fig. 3B, when the relative position of one of the wave guides has been shifted to the extent to bring about a condition of partial register of the openings, part of the supplied power will be delivered through the right-hand end of wave guide 11, and part of the supplied power will be delivered through the right-hand end of wave guide 13. With the openings registering to an extent corresponding to one-half of the extent required for full power transfer, the supplied power is equally divided between the respective right-hand exit ends of wave guides 11 and 13.

When the openings are in full register, as in Fig. 3C, the openings being the optimum length for the wave guide dimensions and the wavelength of the supplied energy, full transfer is effected, so that the energy entering wave guide 11 at its left-hand end is entirely transferred into wave guide 13 and proceeds outward through the right-hand end thereof. Assuming no impedance discontinuity at the right-hand end of wave guide 13, there is no energy reflection therefrom. If a mismatch condition were present in the right-hand end of wave guide 13 or therewith in the conduit system, some energy would be reflected back to the leftward therein, and would be entirely transferred into wave guide 11 to proceed toward the source 31 coupled thereto.

Unless special means are provided for insuring a substantial zero-impedance condition between the contiguous walls it is necessary that they be maintained under pressure, holding them tightly in contact. Otherwise energy leakage would result, and moreover, the behavior of the transfer system would be somewhat erratic.

An arrangement obviating the direct contact between the two wave guides is illustrated in Figs. 5, 6, 7 and 8. This structure comprises a lower wave guide 11' and an upper wave guide 13', arranged generally along the lines of wave guides 11 and 13 of Fig. 1, but with their adjacent narrow walls separated by a very narrow gap. A choke joint system is provided external of the gap along a length appreciably greater than the length of the openings in the wave guides 11' and 13', and a system of mechanical bearings is provided for maintaining the proper close spacing between the wave guides 11' and 13' and permitting guided relative longitudinal motion.

The mechanical supporting system includes a pair of downwardly extending side plates 61 and 63 affixed to the upper wave guide 13', these side plates being vertically disposed and being separated from each other by a dimen-

sion appreciably greater than the cross dimension of the wave guides 11' and 13'. Near the lower edges of the plates 61 and 63 are provided V-grooves, to form portions of ball races for the bearing system. Corresponding 5 V-grooves are provided in members 65 and 67 attached to the sides of wave guide 11', and further V-grooves for the outer ball races are provided in angle members 69 and 71 which include vertically extending sections parallel to and outwardly disposed from plates 61 and 63, respectively. Four series of hardened balls 73, 75, 77 and 79 are situated in the longitudinal ball races thus provided, for accurately maintaining the relative positions shown in the cross-sectional view of Fig. 6 while permitting freedom of longitudinal movement.

15 Referring to Figs. 6, 7 and 8, a series of choke tines exemplified by tines 81 are provided alongside wave guide 11'. The tines 81 are downwardly dependent from wave guide 13', and are spaced by a very small dimension from the outer wall surface of wave guide 11'. These tines 20 are preferably substantially one-quarter wavelength long or very slightly shorter than one-quarter wavelength, their width dimensions being appreciably smaller than their length and the spacing between successive tines being preferably smaller than their width. A similar row of tines 83 is provided at the opposite side of wave guides 11' and 13'. The features of the choke joint per se, embodying the series of tines arranged generally as above described, are set forth and claimed in application Serial No. 197,063 of Kiyo Tomiyasu, filed concurrently herewith, 25 and entitled "Choke Joint System."

If desired, a pointer 45' may be provided on side plate 30 63, and a scale of relative transfer values for cooperation therewith may be provided on the upper horizontal surface or on the exposed side surface of angle member 71, 35 attached to wave guide 11'.

The choke joint system 81, 83, by virtue of the high 40 impedance between the open-circuit lower ends of the tines 81 and 83 and the outer wall surface of wave guide 11' adjacent thereto, produces substantially zero impedance between the adjacent edges of the side walls of wave guides 11' and 13'. By the use of the separate tines rather than a longitudinally extensive sheet of material having the same extent of downward projection, propagation of energy in the choke region parallel to the longitudinal axes of the guide is substantially suppressed.

45 The theory of operation which at present is believed properly applicable to the variable transfer directional coupler systems of the present invention involves the 50 consideration of two modes of wave energy propagation which prevail within the mutually adjacent wave guide portions whose interiors are exposed to each other through the longitudinally extensive openings in the respective guides. It is customary to design a rectangular wave 55 guide for efficient transmission of energy of a known frequency, the mode of transmission being a fundamental mode of the guide usually referred to as the $TE_{1,0}$ mode. This is the dominant transverse electric mode. The "a" dimension of the simple rectangular wave guide ordinarily is such as to prevent it from transmitting energy of this 60 frequency in any of the known higher modes.

When two of such wave guides are juxtaposed with 65 their narrower faces mutually adjacent, and the adjacent narrower walls are opened throughout an appreciable longitudinal extent, the effect is to substantially double the "a" dimension of the wave guide portion. This wave 70 guide portion is then capable of supporting energy in two modes of propagation, the first being the simple transverse electric mode $TE_{1,0}$ described in connection with the basic wave guide section, and the second mode being the "asymmetrical" mode designated $TE_{2,0}$. The transverse electric field vectors representing the first of these modes are illustrated in solid line in Figs. 10A and 10B, and the electric field vectors representing the latter of these modes are illustrated in dotted lines in Fig. 10B.

75 Energy introduced through the lower half of the double

width wave guide, in the $TE_{1,0}$ mode (Fig. 10A), is capable of exciting both of the modes represented in Fig. 10B, the resulting excitation phase being as illustrated by the vector directions in this view. It will be observed that the electric vectors of respective $TE_{1,0}$ and $TE_{2,0}$ modes are cophasal in the lower half of the effectively enlarged wave guide portion, while the phase vectors are mutually opposed in the upper half of the broad wave guide.

Thus, with reference to Figs. 1 and 3, the field intensity distribution in the lower half of the double-width wave guide portion, just to the right of the commencement thereof, is such as to have strong energization in the lower half and very weak energization in the upper half, the latter due to the phase opposition of the two modes.

Now, if the energy component of the $TE_{1,0}$ mode illustrated in solid line in Fig. 10B and the energy component of the $TE_{2,0}$ mode illustrated in dotted line in this same view were propagated at equal speeds along the double-width wave guide portion, shown in Fig. 9 as extending from station 10-B to station 10-C, the wave energy would continue to be substantially confined to the lower half of the volume bounded by the abutting side walls of the juxtaposed wave guide structures. But the two modes illustrated in Fig. 10B are not propagated at equal velocities, the velocity of propagation of the simple transverse electric mode $TE_{1,0}$ (the mode characterized by symmetry of the electric vectors) being slower than the phase velocity of propagation of the $TE_{2,0}$ (asymmetrical) mode. Accordingly, when the energy has been conveyed an appreciable distance along the juxtaposed wave guide portions, the two wave energy components in the lower half of the juxtaposed wave guides have progressed toward phase opposition; whereas the wave energy components in the upper half of the guides, originally in phase opposition, have progressed toward phase addition or phase reenforcement. Complete transfer of the energy to the opposite wave guide section is achieved by providing communication between the juxtaposed wave guides over just the extent necessary for a relative phase shift of 180° between symmetrical and asymmetrical energy transmission modes, as illustrated in Figs. 10B and 10C, such that the phase vectors of the respective transmission modes in the lower half of the juxtaposed wave guides are opposed in the region most remote from the source (i. e. at station 10-C) and the vectors in the upper portion representing the respective modes of propagation are cophasal.

As is apparent, if the opening between the two wave guides were continued even further, the further phase progression would result in a tendency for the energy to be retransferred to the first wave guide, a doubled length of the exposed openings being sufficient to provide complete restoration of energy into the first wave guide section, the rightward direction of energy propagation being maintained throughout.

A basic design of a variable transfer directional coupler involves entirely open narrow walls of the respective wave guides, where they are juxtaposed, so that the effective wave guide portions thereof have substantially smooth broad walls and substantially no discontinuity at the junctures along the broad walls. This applies to the preceding discussion of operating principles. Either of two important departures may be made, for achieving greater length of the openings for a complete transfer, or for achieving some foreshortening of the openings if desired. For the former purpose, inductance cross-bars may be provided across the opening in one of the two wave guides, providing effective shunt inductive loading for the $TE_{1,0}$ mode. Negligible effective loading is thereby provided for the $TE_{2,0}$ mode, because this mode involves substantially zero transverse electric field between the middle regions of the two broad side walls. With the inductance loading, the phase velocity of the $TE_{1,0}$ mode is increased, to bring its phase velocity nearer to equality with the phase

velocity of the $TE_{2,0}$ mode, thereby requiring a greater length of the openings for complete energy transfer. This is desirable in many applications, for various purposes, one example being to provide such increase of the extent of the relative movement as to enable the user to achieve more ease of adjustment and calibration, or to provide more graduations of the scale.

The opposite effect may be achieved by making the openings narrower than the internal cross-dimension of the wave guides, i. e., making the openings in the form of elongated narrow slits. Shunt capacitive loading for the $TE_{1,0}$ mode is thus accomplished, with the result of decreasing the phase velocity in this mode, and relatively enlarging the margin of phase velocity of the $TE_{2,0}$ mode or asymmetrical mode energy component over the phase velocity of the symmetrical mode component. Accordingly, the length of the openings for 100% energy transfer is foreshortened.

The operation of the present variable transfer directional coupler system may be better visualized by more detailed reference to Figs. 9, 10 and 11. Fig. 9 schematically indicates the source 31 supplying energy through wave guide 11 to a utilization device 33 and/or through wave guide 13 to a utilization device 35. In this figure, the openings of wave guides 11 and 13 are indicated as being in full register, for substantially complete energy transfer, and hence for maximum energization of device 35 and negligible energization of device 33. Fig. 9 serves to indicate not only the cross-sectional planes through the structures corresponding to views A, B, D and C of Fig. 10, but also to indicate the cross-sectional planes corresponding to views A-I inclusive in Fig. 11. In Fig. 10C, the solid line vectors correspond in all respects to the solid line vectors shown in Fig. 10B, representing the even or symmetrical or $TE_{1,0}$ mode, directed to the rightward. The dotted line vectors, representing the energy components of the $TE_{2,0}$ mode, however, are shown as reversed with respect to the $TE_{1,0}$ vectors, so that in the lower wave guide region of Fig. 10C, the energy components are opposed whereas in the upper region, they are additive. Consequently, the energy proceeding onward in wave guide 13 through the plane designated 10-D in Fig. 9 is appreciable, being the vector sum of the cophasal energy components, and substantially no energy is present in the right-hand portion of wave guide 11, due to the phase opposition of the component vectors.

Fig. 11 illustrates this situation in terms of rotating vectors, the positions of the vectors indicating an instantaneous picture of phase distribution over the region from plane 11-A to plane 11-I in Fig. 9. The input voltage vector is represented in Fig. 11A as representing the phase and intensity of energy arriving through wave guide 11 at the plane designated 11-A in Fig. 9. The energy at the next station along the lower wave guide region is indicated as divided between two mode components as shown in the lower portion of Fig. 11B, one component being indicated in solid line as lagging the vector of Fig. 11A by 90° and the other vector being indicated as lagging the input vector by slightly more than 100° . The solid vector in the lower circle of Fig. 11B represents the $TE_{1,0}$ mode energy in the lower wave guide portion, whereas the dotted vector in the lower circle of Fig. 11B represents the $TE_{2,0}$ component energy therein. The upper vector diagram of Fig. 11B represents the phases of the $TE_{1,0}$ energy component (the solid line vector) in the upper wave guide portion at station 11-B of Fig. 9, whereas the dotted line vector represents the $TE_{2,0}$ mode component in the same wave guide region.

The vectors in the lower portion of Fig. 11B would be cophasal, and the vectors in the upper portion would be mutually opposed, but for the lower phase velocity of the $TE_{1,0}$ mode energy, which results in the lesser phase retardation at station 11-B. Fig. 11B thus corresponds almost to the vector energy distribution indicated in Fig. 10B.

Figs. 11C, 11D, 11E, 11F, 11G and 11H indicate the relative phase distribution at the correspondingly designated stations in Fig. 9 at the moment of time chosen for the entire phase examination, the last of these vector diagrams showing that after propagation over an appreciable distance, the component vectors in the upper wave guide have progressed into a substantial phase additive condition and the component vectors in the lower wave guide have progressed into a condition for substantial phase opposition. Accordingly, as indicated at Fig. 11F, substantially zero resultant energy is propagated on to the right in wave guide 11 toward utilization device 33, whereas substantially full intensity energy is propagated to the right through wave guide 13 toward utilization device 35.

The diagrams in Fig. 10 indicate a distribution of the solid line vectors—the $TE_{1,0}$ electric field vectors—substantially according to a 180° sine wave envelope, and the disposition of the dotted line vectors for the $TE_{2,0}$ component substantially according to a 360° sine wave envelope. Hence, it is necessary to take into account the presence of energy in still higher modes, mainly the $TE_{3,0}$ mode, in order to satisfy fully the boundary conditions between the wave energies of Figs. 10A and 10B, and similarly to satisfy fully the boundary conditions between the energy conditions of Figs. 10C and 10D. The 180° sine wave envelope distribution of Figs. 10B and 10C correspond to the enlarged wave guide sections thereof, substantially free from concentrated shunt inductive or shunt capacitive loading.

Where concentrated shunt inductive loading is provided, as with cross bars 23 as shown in Fig. 2, and as indicated schematically in Figs. 12B and 12C by the inductance symbols across the middle regions of the enlarged wave guide section, the symmetrical mode energy is reduced to very low intensity at the middle region. Accordingly, its absolute values of intensity are distributed in substantial correspondence with the distribution of intensity values of the asymmetrical mode, and so there is less necessity for higher modes to play a part in fulfilling the boundary condition requirements where inductive loading is employed.

It is generally desirable to design the variable transfer directional coupler so that in the inter-communicative region the enlarged effective wave guide is of ample size to support the $TE_{2,0}$ mode but is of insufficient size to support the $TE_{3,0}$ mode, avoiding the complications which can result from three different modes having three respective phase velocities.

Where the inductance cross-bars are provided in the opening in one of the wave guides, the latitude in design of the overall width in the intercoupled guide section for prevention of $TE_{3,0}$ mode propagation is enhanced.

It has been pointed out above that the $TE_{3,0}$ mode is instrumental in satisfying the boundary conditions between the vector pictures of Fig. 10A and Fig. 10B, and similarly, between those of Fig. 10C and Fig. 10D. This is true, even though the composite wave guide section is so dimensioned as to prevent efficient transmission of $TE_{3,0}$ mode energy, since the higher modes are then present at the entrance and exit boundaries of the composite wave guide section, but are evanescent.

For the purpose of maintaining substantial continuity of characteristic impedance of each of the two wave guides which together constitute the variable-transfer directional coupler system of the present invention, the greater internal cross-sectional dimension of each wave guide (its "a" dimension) is maintained substantially uniform even through the section containing the opening in its narrower wall, as by the provision of an inside plate corresponding in thickness to the wall thickness of the wave guide, the plate being attached to the narrow wall of the wave guide opposite to the opening. Such a plate 91 is illustrated in Fig. 13, as incorporated in wave guide 13 opposite to the opening 19 therein. No such plate is

provided in wave guide 11, where the inductance cross bars 23 have their inner surfaces spaced from the lower wall by a dimension equal to the spacing between the lower and upper walls of the wave guide.

As illustrated in Fig. 14, where a choke coupling system is employed and there is a slight spacing between the wave guides 11' and 13', the wall 91' is made thicker by an amount equal to the spacing between the wave guides, to maintain uniform total internal height dimensions throughout the wave guide system.

Where no inductance cross bars are employed and there is a continuous opening as illustrated in Fig. 9, a plate is provided in each of the wave guides, the plates 91 and 92 respectively compensating for the omission of the wall portions opposite these plates, to provide for the adjustable-register openings.

In each of the variable transfer directional coupler systems described above, the operating characteristics are substantially independent of the selection of a wave guide 20 end at which to supply energy. Considering Fig. 9, for example, the energy may be supplied at the left-hand end of wave guide 11, as shown, or at the left-hand end of wave guide 13, or at the right-hand end of either of the guides. This holds true, whether or not inductance 25 cross-bars are provided in the opening of one of the two wave guides.

The inductance cross-bars, when included in the energy transmission path in only one wave guide (the opening in the opposite wave guide being out of register therewith), have so little effect as to leave it substantially immaterial whether the energy be normally transmitted through the guide containing the cross-bars or through the opposite guide.

Throughout the foregoing descriptions, one guide is 35 shown as straight at both ends and the other guide is shown as being curved at both ends. The curved ends are provided merely for clearance for the end coupling flanges, and for convenience in attachment of further wave guide sections or devices. Such curved sections 40 may be provided in either guide or in both guides.

Examples of dimensions and operating frequency of three workable variable transfer directional coupler systems are given below:

- Width (I. D.) of wave guide: 0.40 inch
 45 Height (I. D.) of each wave guide: 0.90 inch
 Width of openings: 0.40 inch (i. e., the full internal width of the wave guides)
 Length of openings: $8\frac{1}{4}$ inches
 Number of cross-bars: 21
 50 Spacings between cross bars, center-to-center: 0.375 inch
 For an operating frequency of 9,000 megacycles per sec., cross-bars of 0.040 inch diameter were used.
 For an operating frequency of 10,000 megacycles per sec., cross-bars of 0.032 inch diameter were used.
 55 Cross-bars of square cross-section, with their width equal to the diameter of round cross-bars, were also found to give good results.
 A version without the inductance cross-bars, but with full-width openings, was found to yield the required results at 8,700 megacycles with the following dimensions:
 Width (I. D.) of wave guide: 0.40 inch
 Height (I. D.) of each wave guide: 0.90 inch
 Width of openings: 0.40 inch
 60 Overall length of openings: 2.96 inches
 Length of openings, exclusive of tapered ends: 2.50 inches

Couplers for other frequencies may be dimensioned proportionately from the above data, the dimensions being scaled in direct proportion to wavelength. Where a different relation exists between the wave guide dimensions and the wavelength of the energy to be dealt with, allowance must be made for the resulting change in relative phase velocities in the wave guide. The required changes of dimensions of the coupling openings

or the inductance cross bars, or both, may be determined experimentally, employing the above sets of working dimensions as starting points.

Changes in the number of cross-bars per unit length along an opening, or in the widths of the cross-bars, may easily be carried out for achieving an effective change of length of a given set of openings. For example, if a variable transfer directional coupler system is worked out wherein the openings are not quite sufficiently long for making available the total transfer of energy from the first wave guide to the second, fewer cross-bars may be provided, or the cross-sectional dimensions of the cross-bars may be decreased for the increase of the inductive reactance values. Conversely, if the openings are so long as to permit total energy transfer at a condition of partial register, and this condition is undesirable, the inductance cross-bars may be increased in number or cross-sectional dimensions.

The apparatus of the present invention is readily suited for use in a variety of applications in addition to variable-transfer directional coupling. It may be used not only as a variable power divider, as illustrated in Figs. 3A, 3B and 3C, but also as a power combining manifold device readily adjustable to accommodate plural power sources, whether their power contributions are equal or unequal. Considering Fig. 3B, for example, generator 31 could be replaced by a load, and first and second generators could be coupled to the right-hand ends of the respective wave guides. Assuming the proper 90° phase relation maintained between the first and second source outputs, their total combined power is supplied through the left-hand end of wave guide 11.

For equal contributions by these sources, the relative position between guides 11 and 13 is correct as shown in Fig. 3B. If the source coupled to the right-hand end of wave guide 11 supplied a power contribution only one-third as great as the contribution of the source coupled to the right-hand end of wave guide 13, the latter guide would be repositioned to bring index 45 into register with the "0.75" power mark, the mark for the power at the right-hand end of guide 11 being one-fourth the power at the left-hand end thereof, and thus one-third as great as the power at the right-hand end of wave guide 13. One example of two sources with the required fixed phase relations therebetween would be a pair of klystron output amplifiers or klystron output resonators controlled by a common oscillatory energy circuit.

In all of the foregoing versions of the present invention, the wave guides have been described as stacked one above the other, with their narrow walls adjacent and the openings therein. A version of the present invention can be made with two wave guides side by side, i. e. with broad walls mutually adjacent and with their transverse electric field vectors in alignment. In such an arrangement, the openings in the adjacent broad walls are longitudinal as before, and are preferably much narrower than the wall width, e. g. one-tenth to one-fifth the wall width. This type of variable transfer coupler requires a very long region of communication, in general several times as long as required by a coupler wherein the narrow walls are juxtaposed and provided with openings of sufficient length for complete energy transfer. This type of coupler has very high directivity, but requires precise symmetry of the location of the openings in the broad walls.

This invention is not limited to use with rectangular wave guides of equal sizes. Unequal guides may be used, as may also wave conduits having circular or elliptical cylindrical configuration, or other configurations.

Since many changes could be made in the above construction and many apparently widely different embodiments could be made without departing from the scope thereof, it is intended that all matter contained in the above description or shown in the accompanying draw- 75

ings shall be interpreted as illustrative and not in a limiting sense.

What is claimed is:

1. Variable microwave energy transmission apparatus comprising first and second wave guides each having a rectangular cross section, a narrow wall of said first wave guide being adjacent to and separated from a narrow wall of said second wave guide, said narrow wall of said first wave guide having a substantially rectangular longitudinally extensive opening therein appreciably longer than the width of said narrow wall of said first wave guide, said narrow wall of said second wave guide having a substantially rectangular longitudinally extensive opening therein appreciably longer than the width of said narrow wall of said second wave guide, the length of the rectangular longitudinally extensive openings in said first and second wave guides being at least equal to that length required for full energy transfer from one of said wave guides to the other wave guide when said openings are in full register, one of said adjacent narrow walls including a series of spaced inductance cross-bars across the rectangular longitudinally extensive opening therein, a substantially rectangular plate having a length and width substantially equal to the length and width of said rectangular longitudinally extensive openings and having a thickness substantially equal to the sum of the thickness of the narrow wall of one of said wave guides and the separation between adjacent narrow walls of said first and second wave guides, said rectangular plate being situated within one of said wave guides and extending longitudinally along its narrow inner wall opposite the rectangular longitudinally extensive opening therein, the surface of said plate as measured along its width being contiguous with said opposite narrow wall, and means guiding one of said guides relative to the other for providing longitudinal variation of coupling through the openings in the adjacent walls.

2. Variable microwave energy transmission apparatus comprising first and second wave guides each having rectangular cross-section, one wall of said first wave guide being adjacent to and longitudinally movable relative to one wall of said second wave guide, said one wall of said first wave guide having an opening therein appreciably longer than the width of said one wall of said first wave guide, said one wall of said second wave guide having an opening therein appreciably longer than the width of said one wall of said second wave guide, the lengths of said openings in said first and second wave guides being at least equal to that length required for full energy transfer from one of said wave guides to the other wave guide when said openings are in full register, one of said wave guides including a series of spaced inductance cross-bars across the opening therein, and means guiding one of said wave guides relative to the other and retaining said wave guides in alignment for providing longitudinal variation of coupling through the openings in the adjacent walls.

3. Variable microwave energy transmission apparatus as defined in claim 2 wherein both the openings in the adjacent walls of said wave guides are of substantially equal lengths.

4. Variable microwave energy transmission apparatus comprising first and second wave guides, said first wave guide having a first flat wall portion and said second wave guide having a second flat wall portion adjacent to and longitudinally movable relative to said first flat wall portion, said first and second wave guides having first and second longitudinally extensive openings in said first and second flat wall portions, respectively, for microwave energy communication between said first and second wave guides, the lengths of said first and second longitudinally extensive openings in said first and second flat wall portions being substantially equal to that length required for full energy transfer from one of said wave guides to the other wave guide when said openings are in full register,

one of said wave guides including a series of conductive bars spaced apart and extending transversely across the opening in said flat wall portion, and means for guiding one of said wave guides for longitudinal movement relative to the other of said wave guides for variation of the extent of registry of said openings.

5. Variable microwave energy transmission apparatus as defined in claim 4, wherein said first and second wave guides have rectangular internal cross-sectional outlines, said first and second wall portions being the mutually adjacent narrower wall portions of the respective wave guides, and said openings being as wide as the internal width dimensions of said first and second wall portions.

6. Variable microwave energy transmission apparatus as defined in claim 5, wherein said first and second mutually adjacent wall portions are spaced apart, said spacing being very small compared to the width of said adjacent wall portions, said variable microwave energy transmission apparatus including energy leakage suppression means for inhibiting the escape of microwave energy through the space between said first and second flat wall portions.
